(57) **CLAIM**

The ornamental design for a bag, as shown and described.

DESCRIPTION

FIG. 1 is a perspective view of a bag showing my new design where the bag is in a first configuration of use;

FIG. 2 is another perspective view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof;

FIG. 8 is a bottom plan view thereof; and,

FIG. 9 is a perspective view of the bag where the bag is in a second configuration of use.

The short thick evenly spaced broken lines in the drawings depict stitching and form no part of the claimed design. The long thin evenly spaced broken lines in the drawings depict portions of the bag and form no part of the claimed design.

1 Claim, 9 Drawing Sheets
